UNITED STATES PATENT OFFICE.

BENJAMIN ROSENBERG, OF BROOKLYN, NEW YORK.

DISPLAY-RECEPTACLE.

1,306,632.

Specification of Letters Patent. Patented June 10, 1919.

Application filed May 3, 1918. Serial No. 232,374.

To all whom it may concern:

Be it known that I, BENJAMIN ROSENBERG, a citizen of the United States, residing in Brooklyn, in the county of Kings and State of New York, have invented certain new and useful Improvements in Display-Receptacles, of which the following is a specification.

My invention relates to improvements in receptacles; particularly receptacles of the type adapted to be maintained in position to display the contents.

The object of my invention is to provide a receptacle comprising a body and a cover therefor; the body having a support capable of being collapsed and folded against the body when the cover is applied to close the receptacle; and of being expanded and so disposed under the body as to elevate it for exhibition when the cover is removed and the receptacle opened. Preferably the cover is of the telescoping type; but not necessarily so; as under some circumstances, and with some forms of my invention, an ordinary sliding cover will do; and the entire receptacle is adapted to be easily and cheaply manufactured, of simple design, and yet highly efficient to serve its intended purpose.

Other objects and advantages of my invention will appear from the following specification, in connection with the accompanying drawings. The embodiments shown, however, are not the sole constructions by which my invention can be practised; and I desire this disclosure to be construed as explanatory only; and reserve the right to make changes in the various members constituting my receptacle, without altering its essential character, to the full extent indicated by the general meanings of the terms in which the claims appended hereto are expressed.

On the drawings,

Figure 1 is a side elevation of my improved receptacle when the same is set up to present the contents for sale;

Fig. 2 is a top plan of the body of the same; as it appears when set up as in Fig. 1;

Fig. 3 is a top plan of a blank of suitable material, out of which my improved receptacle can be made;

Fig. 4 is a side elevation, partly in section, showing my improved receptacle with the parts thereof in position for storage or shipment;

Fig. 5 is a detail view showing a portion

of the blank illustrated in Fig. 3 modified so as to provide a display section or panel which is an integral part of the blank and is used to bear advertising matter on one face when the blank is folded and the receptacle set up;

Fig. 6 is a rear view of a receptacle constructed out of a blank made as shown in Fig. 3, but modified as indicated in Fig. 5 and set up in display position in the same manner as illustrated in Fig. 1;

Fig. 7 is a detail view partly in section, similar to Fig. 4, showing how the parts of the receptacle of Fig. 6 appear when the same is closed by the lid or cover 2;

Fig. 8 is a view of another blank out of which a receptacle can be made and set up for display in a slightly different fashion;

Fig. 9 is a view similar to Fig. 1 showing a receptacle made out of the blank illustrated in Fig. 8, with the parts of the same in such position as to present the contents to view;

Fig. 10 is a top plan of the receptacle of Fig. 9;

Fig. 11 is a view similar to Fig. 7 showing how the receptacle of Fig. 9 will appear when closed by the cover 2;

Fig. 12 is a view of a detail;

Fig. 13 is a perspective view of another form of my improved receptacle;

Fig. 14 is a side view of another embodiment of my invention;

Fig. 15 is a side view of the construction shown in Fig. 14, but with the parts in different position; and

Fig. 16 is a bottom plan of the last-named embodiment of my invention as the parts appear in Fig. 15.

The same reference numerals identify the same parts throughout.

Referring first to Figs. 1, 2, 3 and 4 I make my improved receptacle comprise a body 1 which can be displayed as in Fig. 1; and a cover 2 for closing the body, indicated by broken lines in Fig. 4. When the receptacle and its contents are to be put on view, the cover is removed and the body 1 is elevated at one end by means of a collapsible and expandable support 3, which is attached to the body, and maintains the latter at an incline; thereby holding up the body and contents in a manner that will attract the attention of prospective purchasers. The back of the support 3 is indicated by the numeral 4, and is movably connected to the

receptacle; being preferably hinged to that end of the body 1 which is to be elevated; and the support 3 has sides 5 with terminal portions 6, which are united to one another 5 at their ends, as indicated in Fig. 2. These sides 5, together with the united ends 6 can be collapsed or folded against the member or back 4; and then, with the latter, turned up against the adjacent end of the body as 10 indicated in Fig. 4. When the cover 2 is applied, it engages not only the body 1, but also the support 3, and holds it against the adjacent end of the body; so that the receptacle looks like an ordinary box or receptacle, except when the cover 2 is lifted.

Referring now to Fig. 3, I provide the blank out of which my improved receptacle can be made with a section 7 for forming the bottom of the body 1. At one extremity 20 of the section 7 is a section 8 for forming one end of the body; this section having lateral extensions 9. Along the sides of the section 7 further I provide sections 10 for forming the sides of the receptacle, and these 25 sections each have an extension 11. All of the aforesaid portions 7, 8, 9, 10 and 11 are marked off from one another by means of score line 12, about which the cardboard or other material utilized in the manufacture 30 of the blank can be folded or bent when the box is given its shape. At the opposite end of the section 7 is a section 14 in line with another section 15. These two sections 14 and 15 are each of practically the same 35 length and width as the section 8; and the section 15 also has terminal extensions 9.

To form the box, the section 8 is bent up at a right angle to the section 7, and the extensions 9 move toward each other over 40 the sections 10 and 11 until the sections 9 are parallel or at right angles to the section 8. Also, the sections 14 and 15 are bent upward, and the section 15 is then bent downward against the face of the section 14 which 45 is the lower face in Fig. 3; whereby the section 14 forms the inner end surface of the box and the section 15 the outer end surface. The extensions 9 carried by the sections 15 are then turned toward each other over the 50 sections 10 and 11 until they are likewise parallel and extend toward the section 8. Next the sections 10 are bent upward until they are in contact with the outer faces of all the extensions 9; that is to say, the faces 55 of the extensions 9, which are the lower faces thereof in Fig. 3; and the extensions 11 are then folded down over the extensions 9 so that these extensions will lie between the sections 10 and the extensions 11 at both 60 sides of the body 1. In order to hold the sides and ends of the body in this position, the bottom of the body may be provided with tabs 13; which are cut out from the bottom, and are adapted to be bent upward 65 so as to engage the free edges of the exten-

sions 11 in the body 1; and maintain the extensions 11 on the inside of the body 1, and against the sections 10. In this way the sections of the body are prevented from springing back out of true position. Of course, 70 the sections 14 and 15 are delineated from each other and from the section 7, and the extensions 9 from the sections 15 by means of score lines similar to the score lines 12 above mentioned.

The member forming the back 4 of the support 3 is integral with the section 15, and marked off therefrom by another score line 12. The length and width of the back 4 of the support is about equal to the length 80 and width of the section 15, so that it can coincide with the section 15 when the support is collapsed and pressed against the end of the body, as shown in Fig. 4. The portions forming the sides 5 of the support 85 are in the shape of lateral extensions from the ends of the back 4; and marked off by additional score lines; and the edges of these extensions on which the body 1 of the receptacle rests run off from the corners of the 90 section 15 at the required angle. The other edges of the sides 5 are, of course, in line with each other, and with the end of the back 4. Both the sides 5 are provided with two transverse score lines 16, to enable these 95 sides to be bent and folded, so that the ends 6 may be united and the support be collapsed.

After the body of the box is formed, as above described, the extensions 5 at the opposite ends of the back 4 are bent toward each other; each about the score line 16 adjacent the end 6 thereof; and the extremities 6 are secured together; as by pasting, or by means of some suitable mechanical 105 fastener. The direction in which the sides 5 are bent is downward with reference to the position of the parts shown in Fig. 3; and after the ends 6 are joined, the sides 5 will be bent about the remaining two transverse creases or score lines 16 between the ends 6 and the back; so that the sides 5 and ends 6 can be folded flat against the back 4 when the support is to be turned up against the section 15, as in Fig. 4. When the receptacle is to display the merchandise in it, 110 the support is turned downward and disposed under the box, and the sides 5 distended, as shown in Fig. 1. Hence the receptacle will be maintained in elevated and 115 inclined position.

From the above description it may be seen that my improved receptacle is of simple and yet efficient construction. There are but few parts, and the manipulation of these to 125 insure the desired result is quite easy. When the receptacle is closed, the stand is entirely hidden, and when the cover is removed, it is but the work of an instant to set the body 1 up.

The cover 2 may be of any desired construction, and while I have shown the body of the receptacle as being preferably made from a single blank of cardboard, I may obviously make it of several pieces pasted or otherwise secured together to afford the same result, if desired.

In order to attract attention to the receptacle when set up, as shown in Fig. 1, I may apply thereto a show card or display panel indicated at 17. This panel 17 will consist of a piece of cardboard or the like having one end inserted into the box at the end which is elevated by the support 3; preferably by thrusting this end in between the elevated end 14 of the box and the contents of the same. This show card may have a transverse crease therein at the level of the upper edges of the box to enable it to be bent rearward at a slight angle.

If desired, I may utilize a member 18, such as a strip of rubber or the like elastic material, or even a light coiled metallic spring, fastening one end to the united extremities 6 of the extensions 5 of the member 4 and the other end to the lower face of the bottom 7 of the box 1. When the support 3 is collapsed against the end of the box, this member 18 will be stretched and put under considerable tension; but as long as the lid 2 engages the support 3 this support will be held against the end of the box 1. When, however, the lid 2 is taken off, the member 18 will draw the support 3 down under the box 35 and distend it automatically into the position shown in Fig. 1. I may utilize this member 18 or omit it, as desired.

It will be seen that the support 3 thus constitutes means to maintain the body in position to display the contents as soon as the cover is removed.

Instead of making the display panel 17 as a separate member in the manner shown in Figs. 1 and 2, I may make this display panel in such a way that it will be an integral part of the blank; so that when the blank is folded to produce the box or receptacle, the showcard or display panel can be set up in display position merely by bending it as required. See Figs. 5, 6 and 7. Fig. 5 presents the show card 19 as cut out from the stock making the section 15 and the back member 4. It begins at the score line 12 between the section 15 and the section 14, and will generally be long enough to extend a material distance into the member 4. Hence the score line 12 between the section 15 and the member 4 will not run the entire width of the blank between these two parts, but will stop at the sides of the display panel 19. Otherwise, the blank shown in Fig. 5 will be the same as the blank shown in Fig. 3. When this blank is folded to make a box, the section 19 will be hinged to the upper edge of the rear section 14 along the same

line as the section 15; and when the section 15 is bent down against the section 14 so as to bring the score line 12 between the section 15 and the member 4 into position along the lower edge of the rear end of the box, 70 to permit the support 3 to be collapsed and folded against the rear end of the box, or extended and disposed under the bottom, the display panel 19 will remain hinged to the upper edge of the rear end of the box; and 75 can be caused by the operator's fingers either to assume a substantially upright or display position, as shown in Fig. 6 when the box is set up for display; or to be bent down in a forward direction, so as to lie upon the top 80 of the contents of the box, when the support is collapsed against the end of the box and the lid 2 is applied, as in Fig. 7.

In the foregoing description the support is shown as being hinged to the body of the box 85 or receptacle; in such a way that when it is disposed under the box, the rear end of the box or body will rest thereon. I may also construct the blank out of which the box or receptacle is made in such a fashion that the 90 support will be hinged to the opposite end of the box, so that when the support is manipulated at this end to expand it, the box or receptacle will be set up for display by resting upon the support 3 at the front or lower 95 end of the box. See Figs. 8, 9, 10 and 11. In Fig. 8 the blank is shown substantially the same as the blank of Fig. 3, except that in place of the member 4 in line with the section 15 and of the same width or depth, I 100 utilize a member 20, which extends transversely of the blank 7 and is of considerable less width or depth than the member 4. This member 20 is marked off from the section 15 by a score line 12, and the ends of the member 20 are made integral with a pair of extensions 21. These extensions correspond to the sections 5 previously mentioned; only instead of becoming narrower away from the member 20 they become wider and they are 110 provided on their outer ends with extremities 22. These extremities preferably have parallel edges and they are marked off from the extensions 21 by score lines 16. Further, between these score lines 16 115 and the score lines 12 delineating the sections 21 from the member 20, I place score lines corresponding to the score lines 16 in Fig. 3 which are nearest to the member 4. At the opposite end of the blank I may provide a display panel 19 making it integral with the section 8 and separated from it by 120 a score line 12.

When this blank is folded to make the box, the section 14 will be bent upward and the section 15 downward, as before; and the member 20 can be turned up so as to lie against the face of the section 15 opposite the other face of this section which will be in contact with the outer face of the section 130

14. The extensions 21 can then be bent toward each other, whereby they will be caused to extend away from the sections 14 and 15 and the member 20; and these sections can then be bent about the score lines 16 nearest to the member 20 and then about the score lines 16 between them and the extremities 22; so as to cause the extremities 22 to extend transversely of the length of the box 10 and come together. These extremities of course will be fastened to each other the same as the extremities 6 of Fig. 3. The support thus provided can then be collapsed against the end section 15, the parts bending 15 about the lines 12 between the member 20 and extensions 21, the lines 16 across the extensions 21, the lines 16 between these extensions and the extremities 22. When the cover is applied after the support is collapsed against the end of the box, the parts will have the position shown in Fig. 11. On the other hand, when the box is set up for display, the support will be folded down under the box and the parts will have the 25 position shown in Figs. 9 and 10. In the embodiments of my invention illustrated in Figs. 8, 9, 10 and 11, it is of course necessary that the extensions 21 and the extremities 22 be long enough to make the support extend from the forward or lower edge 30 of the box when set up toward the rear elevated end a sufficient distance to enable the body of the box to rest securely on this support and thus reduce the liability of the box 35 to get upset when something happens to strike against it. By the support being hinged to the front end of the box, the box when set up for display can be supported at a much greater incline than when the support is hinged to the rear end of the box. This fact will be clearly seen by a comparison of Fig. 9 with Fig. 1.

The extremities 6 and the extremities 22 may be secured together by either pasting or 45 by means of mechanical fasteners or in the manner shown in Fig. 12. In the last named view the extremities are provided with slots 23; one of these slots extending into one extremity from one longitudinal edge thereof 50 about half way across the width of the same toward the opposite edge, and near the terminal edge of this extremity. The other extremity has a similar slot beginning at the opposite edge near the terminal edge of the 55 same and likewise extending about half way across the width of this extremity. With this construction one simply interlocks the extremities in order to hold them together, moving the end of each into the slot provided by the other. The inner ends of these slots 23 thus come together and the extremities 22 will be in alinement.

In Fig. 13 I show another embodiment of my improved box which is provided with 60 panels 24 that may be inserted into the box

along the sides and between the sides and the contents. These panels 24 are scored lengthwise, as shown at 12, so that they may be either folded down upon the contents of the box or bent over outward as Fig. 13 indicates. When bent as shown they serve as means extending along the sides of the box to bear advertising matter on their upper faces. These panels 24 may be used either with or without the show card 17 or 19, and 70 may be applied to the box when the support 3 is attached thereto either at the front end or the rear end.

In Figs. 14, 15, 16, I illustrate another form of my invention, wherein a collapsible support is secured to the bottom of the body 1 of the box or receptacle. The support as a whole is indicated by the numeral 25. It comprises a pair of triangular or wedge-shaped sides 26 connected by a transverse 80 end 27. Both the sides and the end have hinged connection with a top 28 and this top may be joined to the front edge of the body 1 by means of a section 29.

The body 1 may be of course made of a 90 single blank of cardboard folded into the proper shape with its ends and sides secured to each other in the same manner as the end 8 and sides 10 illustrated, for instance in Fig. 3; and the section 29 may be of the same 95 length and width as the adjacent end of the box and be connected to the adjacent end by means of a score line or hinge, such as the score line 12 between the section 15 and the back 4 in Fig. 3. The portion 28 may be 100 connected to the portion 29 by means of a similar hinge or score line; the sides 26 beginning at this latter score line and having their pointed ends located on its extremities, so that these sides widen toward the opposite 105 end of the portion 28. The sides 26 and end 27 will be hinged to the portion 28 and the end 27 and the extremities of the sides 26 may be secured to each other in any suitable way. By this construction I am enabled to 110 make the body 1 and the support 25 in one piece. After the body 1 is made up the portion 29 is turned down against the adjacent end of the body and the parts 26, 27 and 28 are turned under the body; and preferably the portion 28 is pasted against the bottom 115 of the body to hold it in place.

In order to secure the end 27 to the sides 26, I may provide either the end 27 or the sides 26 with extensions and secure the sides 120 and end together either by pasting or interlocking. For example the sides 26 may have extensions similar to the extensions 9 on the part 8 in Figs. 3 and 8 and the end 27 may be made with an extension like those 125 shown at 11 on the sides 10. The extensions of the sides 26, when these sides are turned at right angles to the part 28, may be bent toward each other and the end 27 folded up against them and then over them; the exten- 130

sion on the end 27 being engaged by a tab, similar to the tab 13 above-mentioned, in the portion 28 to hold it in place. I do not illustrate the structural details mentioned 5 because they are already clear enough in the preceding views, and furthermore it is not essential to my invention that any particular method of connecting the sides 26 and end 27 be adopted.

10 When this box is set up it will appear as in Fig. 14, the wedge-shaped sides widening away from the portion 29. To enable the support to be collapsed so that the box may be stored or shipped I provide the sides 15 26 with diagonal score lines 30 which mark off triangles 31 adjacent the end 27; these diagonal lines 30 extending from the lower edge of each side upward and rearward and terminating at the right-angled corner of 20 the side where it joins with end 27. To collapse the box the sides are turned over toward each other, being folded along the score lines 30, until they lie against the top 28. The portions 31, however will rest 25 against the outer face of the sides and the end 27 will rest upon these triangular portions as shown in Figs. 15 and 16. With the stand or support 25 collapsed as these two figures illustrate, I can fill the box and 30 thrust it into a slip cover. When the cover is removed the parts of the support can be distended and set up at once as in Fig. 14. To do this the sides 26 and ends 27 require only to be manipulated by one's fingers and 35 the sides pushed outward far enough to bring the portions 31 and the remainder of the sides in the same plane. The stiffness of the material will then be sufficient to hold the sides and the end 27 in proper position to display the body 1.

In the blank shown at Fig. 3, the sides or extensions 5 are shown as having only one score line 16 while in the blank shown in Fig. 8 the sides or extensions 21 have several such transverse score lines making a somewhat longer stand or support. It will be evident however, that the size and other characteristics of the support will be governed by the design of the particular case.

50 Having described my invention, what I claim to be new, and desire to secure and protect by Letters Patent of the United States is as follows:—

1. A receptacle comprising a body and a member movably connected to one end thereof and having lateral extensions, said extensions being bent with respect to said member and united at their ends, said extensions also being capable of being collapsed against said body, and of being dis-

posed under the body and expanded to enable said body to rest on same.

2. A receptacle comprising a body, a member movably connected thereto, and extensions connected to said member and extending at angles to said member and being united at their ends, said member and said extensions being capable of being folded against the body, said member and said extensions being also capable of being disposed below the body and the extensions distended under the same to provide a support for said body. 65

3. A blank for a receptacle, comprising sections for forming a bottom, sides and ends, and a member hinged to one end section and having lateral extensions, said extensions being capable of being united and folded to provide with said member an expandable and collapsible support. 75

4. A receptacle comprising a body, a cover, and a collapsible support movably connected to one end of the body, the support being adapted to be disposed below the body and being expandable to maintain the body in position to display the contents when the cover is removed. 85

5. A receptacle comprising a body having a support movably connected thereto, and adapted to be collapsed and folded against one end of the body, or expanded and disposed below the body to maintain the body in position to display its contents. 90

6. A receptacle comprising a body, a support movably connected thereto, said support being capable of being collapsed against the receptacle or expanded and caused to maintain the receptacle in position to display its contents, and a member engaging the receptacle and the support for automatically expanding the latter. 100

7. A receptacle having a support movably connected to one end, the said support being capable of being collapsed against said end or expanded and caused to maintain the receptacle with said end elevated. 105

8. A blank for a receptacle comprising sections for forming a bottom, sides and ends, and a member hinged to one end section and having lateral extensions, said extensions being capable of being united and folded to provide with said member an expandable and collapsible support, said blank also having an integral portion providing a display panel located adjacent said member and the end section hinged thereto. 110

In testimony whereof, I have signed my name to this specification this 5th day of March 1918.

BENJAMIN ROSENBERG.
